(57) **CLAIM**

I claim the ornamental design for a cell phone grip stand, as shown and described.

DESCRIPTION

FIG. 1 is a perspective view of a cell phone grip stand showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof, and,

FIG. 8 is a perspective view thereof, illustrated in a folded position.

1 Claim, 8 Drawing Sheets
